UNITED STATES PATENT OFFICE.

DELL W. NICHOLS, OF MINNEAPOLIS, MINNESOTA.

THERAPEUTIC LAMP APPLIANCE.

Application filed March 18, 1924. Serial No. 700,106.

To all whom it may concern:

Be it known that I, DELL W. NICHOLS, a citizen of the United States, residing at Minneapolis, in the county of Hennepin and State of Minnesota, have invented certain new and useful Improvements in Therapeutic Lamp Appliances, of which the following is a specification.

This invention relates to a therapeutic 10 appliance, and has for its object to provide an appliance of such class, in a manner as hereinafter set forth, with means, whereby the lamp, forming an element of the appliance, can be adjusted so that application of 15 the light rays can be had at the desired point with respect to and without any inconvenience to the patient.

A further object of the invention is to 20 provide, in a manner as hereinafter set forth, a therapeutic appliance including an adjustable lamp support having means to permit of the lamp being adjusted to various heights, as well as, whereby the lamp can 25 be positioned at any desired angular direction.

Further objects of the invention are to 30 provide, in a manner as hereinafter set forth, a therapeutic appliance, which is simple in its construction and arrangement, strong, durable, compact, adjustable, thorough and 35 convenient in its use, readily assembled, and comparatively inexpensive to manufacture.

With the foregoing and other objects in 35 view, the invention consists of the novel construction, combination and arrangement of parts as hereinafter more specifically described, wherein is shown an embodiment of 40 the invention, but it is to be understood that changes, variations and modifications can be resorted to, which fall within the scope of the claim hereunto appended.

In the drawings, wherein like reference 45 characters denote corresponding parts throughout the several views:—

Figure 1 is an elevation of a therapeutic 50 appliance in accordance with this invention.

Figure 2 is a fragmentary view upon an 55 enlarged scale in vertical section.

Figure 3 is a fragmentary view in section 60 illustrating the frictional clamp for the adjustable section of the stand.

Figure 4 is a vertical sectional view of light rays directing element.

Figure 5 is an inverted plan thereof.

A therapeutic appliance in accordance 55 with this invention includes an adjustable lamp supporting standard, a flexible hanger, a coupling member for the hanger, a lamp carried by the hanger, a directing element 60 for the light rays, and a base for the standard.

The adjustable supporting standard is of 65 the telescopic type and comprises a lower tubular section 1 and an upper tubular section 2, which extends in the upper end of the section 1 and further is vertically adjustable relative to the said section 1. The supporting standard is constructed of any suitable metallic material.

The section 1 is provided at its upper end 70 with peripheral threads 3 and at its lower end with a reduced peripherally threaded terminal portion 4, and above the latter carries an adjustable threaded collar 5.

The standard is connected to and supported by a base consisting of a hollow body portion 6 and a cover 7 therefor, and each of which is formed from metallic material, 80 and with the body portion 6 of materially greater weight than the cover 7, and further with the latter conforming in contour to and snugly fitting the outer face of the body portion 6.

The base is open at its bottom and has a 85 closed top flattened centrally thereof, as at 8. The base preferably is circular in contour, but it is to be understood that it can be of any shape desired.

The body portion 6, centrally of its top 90 is formed with an opening 9 having its wall threaded, and said cover 7, centrally thereof is provided with an opening 10, which registers with the opening 9.

The reduced lower terminal portion 4 is 95 extended through the opening 10 and has threaded engagement with the wall of the opening 9 whereby said section 1 is secured in an upright position by the base. The collar 5 is adjusted downwardly in the section 1 to 100 engage the flattened portion 8, of the base, so that the cover 7 will be tightly clamped to the body portion 6.

The section 2 of the standard, at its up-

per end is provided with peripheral threads 11, and said section 2 has its lower terminal portion 12 provided with a pair of diametrically opposed insets 13, forming a pair of 5 lengthwise extending grooves 14 opening at their lower ends at the inner end edge of said section 2.

At the upper end of each of the grooves 14, the section 2 is formed with an opening 15, 10 for the purpose of pivotally connecting to the section 2 a depending resilient frictional clamp formed from a single length of spring wire.

The frictional clamp comprises a pair of 15 side portions each having an outwardly inclined upper part 16 of substantial length, and an inwardly inclined lower part 17, preferably of greater length than the upper part. The upper part 16 of one side portion 20 extends in an opposite direction with respect to the upper part 16 of the other side portion. The lower parts 17 of said side portions not only extend inwardly at an inclination towards each other, but further extend outwardly at an angle with respect to the direction in which the upper parts 16 extend.

The frictional clamp further includes a 30 top formed of a pair of extensions 18, 19 and each thereof extends inwardly at an angle with respect to the upper end of the upper part 16 of a side portion. The extensions 18, 19 are disposed at an inclination so that they will oppose each other. The 35 extensions 18 and 19 are mounted in the section 2 of the standard, extend in opposite directions with respect to each other and each projects inwardly through an opening 15. By this arrangement the frictional 40 clamp is pivotally connected to and suspended from the section 2.

The frictional clamp further includes a bottom formed of a pair of semi-circular 45 portions 20, 21 and each of which is disposed at right angles to the lower end of a lower part 17. The portions 20, 21 are so disposed whereby one will be offset with respect to the other when the clamp is set up as shown in Figure 3.

50 The frictional clamp further includes a coupling portion formed of a coiled upper part 22 and a pair of oppositely extending depending vertical extensions 23, 24, which oppose the lower parts 17 of the side portions. The extension 23 terminates in the curved portion 20 of the bottom and the extension 24 terminates in the curved portion 21 of the bottom. The coupling member 55 normally maintains the side portions and bottom extended and acts to set up a frictional clamping action between the bottom of the clamp and inner face of the section 1, of the standard at two points.

The upper parts 16 of the end portions 60 are of greater length than the length of the

grooves 14, and the side walls of these latter limit the shifting movement of the side portions. The grooves 14 also provide clearances for the side portions of the clamp so that the section 2 of the standard can be 70 inserted into the section 1 thereof.

The outer diameter of the section 2, with respect to the inner diameter of the section 1, is such as to provide a snug sliding fit between said sections, and after the section 2 has been vertically adjusted, the frictional clamp engaging with the section 1, will hold the section 2 in the position to which it has been adjusted.

Detachably engaging with the threads 3 80 of the section 1, is an inwardly flanged collar 25 through which extends the section 1. The collar 25 imparts an ornamental appearance to the upper end of the section 1.

The flexible hanger which is constructed 85 of metallic material and is tubular, comprises an upper rigid end terminal in the form of a short sleeve 26, having a peripherally threaded reduced upper end 27, a lower rigid end terminal in the form of a short sleeve 28 having a peripherally threaded reduced lower end 29, and an intermediate flexible portion 30, of substantial length and which is fixedly connected 90 to the sleeve 26 and 28.

Interposed between the flexible hanger and the section 2 of the standard, is a coupling member for connecting the hanger to said section 2, and which further provides for the entrance of the circuit connections 10 31 which extend through the hanger to the lamp 32. The coupling member consists of a hollow semi-spherical body 33, having an opening 34 for the entrance thereto of the circuit connections 31:

Integral with and depending from the body portion 33 is an interiorly threaded 11 collar 35, for engagement with the threads 11. Formed integral with the top of and depending within the body portion 33, is an interiorly threaded collar 36 which is engaged by the reduced threaded lower end 29 of the sleeve 28. When the coupling member is secured to the hanger and section 2, the sleeve 28 abuts against the outer face 11 of the top of the body portion 33, which is flattened at such point, as at 37.

The reduced upper end 27, of the sleeve 26, detachably engages with the socket of the lamp 32, whereby the latter will be suspended from the upper end of the hanger and can be adjusted to any desired angular position with respect to the standard.

Mounted on the socket of the lamp 32 12 and inclosing and depending from the globe of the lamp is a directing element for the light rays, and which is in the form of a hood constructed from a single sheet of thin metallic material highly polished on its inner and its outer face. The hood is circular 13

in contour and includes a flaring lower portion 38 of compound curvature in vertical section and which is outwardly beaded at its bottom, as at 39. The hood further includes a frusto-conical intermediate portion 40 into which merges the top of the lower portion 38. The upper circular portion of the hood is indicated at 41, and into which merges the top of the intermediate portion. The upper portion 41 is formed at its top with an inwardly extending apertured annular flange 42 providing means for connecting and suspending the hood from the socket of the lamp. The intermediate portion 40 is of materially greater height than the upper or lower portions 38, 41, and the lower portion 38 is of greater height than the upper portion 41. The openings in the flange 42 are indicated at 43 and provide vents.

If desired the section 1 and cover 7 can be provided with an outer coating of white or colored enamel and the section 2 and hanger have the periphery thereof highly polished.

The adjustable standard permits of the lamp, with the directing element, to be positioned at any desired height, and the flexible intermediate portion of the hanger allows for the lamp and directing element to be set at any suitable inclination so that the light rays from the lamp can be directed

at any desired point upon the patient without any inconvenience.

It is thought that the many advantages of a therapeutic appliance, in accordance with this invention can be readily understood, and although the preferred embodiment of the invention is as illustrated and described, yet it is to be understood that changes in the details of construction can be had which will fall within the scope of the invention as claimed.

What I claim is:—

An adjustable support comprising a base, a sectional standard connected therewith and formed of an adjustable tubular upper section and a stationary tubular lower section, said upper section telescoping in said lower section and having its lower terminal portion provided with lengthwise extending diametrically opposed peripheral grooves, and a contractile frictional clamp provided with right angularly disposed upper ends extending in and pivotally connected to said upper section, said clamp depending from and seating in the grooves of said upper section and further frictionally engaging with the lower section to maintain said upper section in adjusted position.

In testimony whereof, I affix my signature hereto.

DELL W. NICHOLS.
